Hemphill Company, Central Falls, R. I., a
corporation of Massachusetts

Application June 30, 1936, Serial No. 88,197
In Canada September 21, 1935

6 Claims. (Cl. 66—50)

This invention relates to new and useful improvements in devices for forming ornamental pattern work in knitted fabrics such as are commonly produced on multi-feed knitting machines.

5 The case is a continuation as to all common subject matter of applications Ser. Nos. 706,082 and 56,991, respectively, filed in United States.

In the drawings:

10 Fig. 1 is a front elevation of a typical multi-feed knitting machine to which the invention has been applied;

Fig. 2 is a section showing parts of a selecting device applied at one feeding station of a multi-feed knitting machine and the manner in 15 which the novel features of this invention are applied thereto;

Fig. 3 is a detail, partly in section, showing the manner in which one of the lower selecting plungers is controlled by means of the device 20 herein described;

Fig. 4 is a sectional view, greatly enlarged, illustrating certain features of the invention; and

Fig. 5 is an enlarged view, partly in section, showing the invention as applied to one selecting 25 station of a multi-feed knitting machine, the parts being illustrated as seen from above.

Very satisfactory pattern work has been 30 formed on multi-feed knitting machines by means of manually operated plungers controlling needles through jacks or extensions of the needles having removable butts thereon. These unitary selecting devices are provided for each feed of a multi-feed knitting machine as illustrated in the United States applications referred to above, and 35 the different figures and conformations capable of being produced by said machine are dependent only upon the number of feeds spaced about the machine and the number of separate steps of selection provided by each series of manually 40 operated plungers or the like and the removable butts with which they cooperate. Variations in shape of figures and variations as to the appearance of a completely ornamented fabric are practically unlimited.

45 One of the purposes of this invention is to further magnify the possibilities of the basic pattern means herein illustrated and more definitely described and illustrated in the applications above mentioned. By automatic control of certain of 50 the plungers, previously manually operated, it is possible to space the ornamental designs or figures and to vary the pattern effects in different parts of the fabric, this not being practicable with the original mechanism. It is further possible 55 to make figures of greater size and of dif-

ferent proportions than have been found practicable previously.

Referring to the figures of drawings, a multi-feed knitting machine having a frame 1, legs 2, a rotatable needle cylinder 3, and driving mechanism generally indicated at 4 has been shown. The needles may be of the latch type or of the spring beard type and are preferably controlled by a series of unitary cam assemblies 5, only two of which have been illustrated in Fig. 1, but it 10 being understood that a plurality of these cam units must be spaced about the machine equivalent to the number of separate feeding stations employed to deliver yarn to said needles. It is not necessary that the cam structures be unitary and 15 individual for each feed, but they may be grouped or formed about the cylinder as a complete unit. It is further contemplated to apply the invention to knitting machines having stationary needle cylinders and cams movable relatively thereto. 20

Referring to Figs. 2—5, the needle cylinder 3 is shown in greater detail being attached by means of a series of bolts 6 to a large ring gear 7 for driving the same through a pinion 8 which is in turn rotated with shaft 9 by means of 25 bevel gears 10 and 11, bevel gear 11 being rotated from a source of power through pulley 12, a clutch and other necessary gearing (not shown). A ring 13 between cylinder 3 and gear 7 serves to maintain the rotating cylinder assembly in 30 proper relationship to the frame of the machine all in a manner well known in the art. A series of plungers 14, herein shown as twenty in number but not necessarily restricted to any particular number since it is quite possible to 35 employ more or less of the same, are mounted to slide radially in upright elements 15 and 16 suitably supported on the base of the machine. As before stated, a number of these units are spaced about the machine one for each feeding station 40 thereon and it is the intention that plungers be manually set in a position to engage saw-tooth butts 17 on jacks 18 for the purpose of raising said jacks and their cooperating needles so that another butt 19 may engage a cam for raising both 45 jack and needle to take yarn and knit it into a loop at that particular fabric forming station. It is to be understood that the saw-tooth butts 17 are capable of being removed by means of 50 breaking or in any other satisfactory manner, and that these butts will be removed from jacks in accordance with the particular pattern which is to be knitted.

The upper and lower ones of the group of 55 plungers generally indicated at 14 and which

will be hereinafter referred to by numerals 20 and 21 respectively, are not to be controlled manually, but are to be automatically moved to and from butt engaging position by means of 5 levers 22 and 23 pivoted on an upright spindle 24 which has been threaded into the base of the machine. The top plunger 20 functions upon a removable butt or upon a non-removable butt as described later. These levers are maintained at 10 the proper levels to engage plungers 20 and 21 by means of sleeves or spacers 25 and 26. Each lever has a toe 27 and an oppositely directed arm 28, the rounded end of which engages a slot 29 in the end of each of the plungers. A spring 30 attached at one end to arm 28 and at its other end to a suitable connection as shown at 15 31 projecting from element 16 serves to maintain lever 22 or 23 as the case may be and its co-operating plunger inwardly or in the butt engaging 20 position.

Closely adjacent spindle 24 another similar but larger spindle 32 has been threaded or otherwise suitably attached to project upwardly from the base of the machine. A sleeve 33 is rotatable on 25 spindle 32 and has a keyway cut therein for the reception of key 34 extending lengthwise thereof. At the uppermost end of said sleeve and on a level with lever 22 has been mounted a disc 35 having a key slot therein engageable with key 34 so that said disc must rotate with sleeve 33. Another similar disc 36 cooperates with lever 23 and is spaced from the first disc by means of a spacer 37 and from the base of the machine by 30 means of sleeve 38 having integral therewith a ratchet wheel 39. The construction provides for 35 rotating both discs 35 and 36 as ratchet 39 is moved by mechanism hereinafter described. Each of the discs 35 and 36 has a series of butts thereon which are to be removed by breaking or 40 by other satisfactory methods. The toes of levers 22 and 23 ride upon these butts and in the event the toe of one of the levers is allowed to fall into the space left where a butt has been removed, the 45 cooperating lever under the influence of its spring will move its plunger inwardly to engage butts on such jacks as have butts at that level.

Each of the discs 35 and 36 is provided with a plurality of removable butts 40 and these butts may be frangible so that they can be broken 50 off or may be removed in any other satisfactory way. In the illustrated embodiment of the invention I have shown 12 butts on each disc but it is to be understood that any suitable number of butts may be employed. While I have shown one 55 disc operating on the topmost plunger and another on the lowermost plunger, I may employ more discs functioning upon a greater number of plungers depending upon the particular type of pattern work which it is desired to make. For 60 a definite number of plungers it is advisable to limit the number of discs for the reason of retaining as many separate steps served by the manually operated selecting plungers so that the 65 size and shape of individual figures produced for ornamentation will be as great as possible; also, for the sake of simplicity and low cost of construction.

As was disclosed in United States Application 56,991, a hinged element 41 pivoted at 42 serves 70 to hold those plungers which are in operative position inwardly to contact jack butts under the influence of spring 43. This element 41 also locks plungers which are moved out of engagement with jack butts in such a position that those 75 plungers can not accidentally move into operative

position. As has been shown in Fig. 4 this element 41 must not be of a length to contact the top and bottom plungers 20 and 21 since they are to be moved entirely under the control of levers 22, 23 and discs 35 and 36.

Referring to Figs. 2, 3 and 5, a bushing 44 inserted in the base of the machine has rotatable therein a spindle 45. This spindle has adjustably fixed by means of set screw 46 a projecting arm 47 and at the upper end I have secured a lever 48 carrying a pawl 49. Pawl 49 engages the ratchet teeth on ratchet wheel 39 and under the influence of cam 50 attached to the ring gear 7 by means of screws 51, will ratchet the discs 35 and 36 throughout the space of one tooth on the wheel 15 39, i. e., one butt 40, during each revolution of the needle cylinder, this amounting to a complete rotation of discs 35 and 36 every twelve revolutions of the cylinder in the particular embodiment shown and described in this case. 20 Levers 47, 48 and pawl 49 are moved to the position shown in Fig. 3 by means of spring 52 attached to lever 48 and to a screw 53 or to any other fixed projection on the machine. A pin or screw 54 limits movement of a counter-clockwise direction as shown in this Fig. 3. A coil spring 55 is fixed at one end to pawl 49 and at the other to a washer 56 which is incapable of rotating on screw 57 upon which pawl 49 swings. This spring 55 maintains the pawl in engagement 25 with the ratchet teeth. In Fig. 5 these elements are shown just as they have advanced the ratchet and discs 35 and 36 one complete space due to cam 50 sweeping past lever 47.

In the simple embodiment of the invention 35 shown only one cam 50 has been fixed to ring gear 7, but it is to be understood that I may employ more of these cams depending upon the particular type of pattern work which is to be done and upon the number of times during one 40 revolution of the needle cylinder I find it necessary to move discs 35 and 36 to change the position of plungers 20 and 21 during that single revolution.

As shown in Fig. 2 the top plunger 20 functions 45 upon a butt 58 which is not removable as are the other butts 17. This conserves the number of steps afforded by removable butts 17, and plungers 20 are to be used whenever all pattern work is to be discontinued for a complete revolution 50 of the needle cylinder, that is, for as many courses as there are separate feeding stations spaced about the machine. The lower plunger 21 shown functioning upon the bottom removable butt 17 can be used to inhibit the pattern work being 55 done at any group of needles whereupon that bottom butt is maintained at corresponding jacks. It can be seen that the top plunger 20 might also be employed to work on a removable butt and that other plungers might also be controlled 60 by similar discs to increase the number of possible combinations of pattern which I desire to make. It is possible to completely blot out all pattern work for a number of courses, or certain predetermined figures in the pattern may be discontinued for a plurality of courses and then other figures discontinued for courses following to space said figures according to a great number of possible combinations all tending to give the knitter a much greater choice of design which 70 will be apparent on the finished fabric.

As an example of the first type of work, assume that diamonds or any other shaped figures are being produced on a multi-feed machine, these figures being of maximum size according to the 75

number of feeds and the number of manually controlled selecting plungers available. By use of the manually controlled plungers only, such a machine would complete a series of these figures on each revolution so that the said figures would not be spaced in a course-wise direction. During the production of such figures on one revolution of a machine none of the automatically controlled plungers would be in active position, however, on starting the next revolution of the needle cylinder, cam 50 would strike levers 47 ratcheting each disc throughout the space of one tooth so that levers 22 will project plungers 20 into a position to engage jack butts 58, it being understood that as cam 50 rotates about the machine this movement of the pattern discs takes place at every feeding station to nullify the pattern work at that feed. According to the presence or absence of butts 40 on the pattern discs the top plungers 20 may remain in position for one or more revolutions thus preventing the pattern from appearing on the fabric during these revolutions. Just as soon as lever 22 at each feed is caused to move its plunger out that feed will again function to produce its part of the pattern.

In the second example it would be necessary to employ top plungers 20 and bottom plungers 21, these plungers working on groups of jacks some having butts broken away at the top others having their lower butts broken off. In one revolution the top plungers may be brought in working upon certain butts left on jacks so that alternate figures, for example, will be prevented from appearing on the fabric, and during the next revolution, the bottom plungers will be brought in while the top plungers move out so that the intermediate figures will cease to appear on the fabric. In this way the pattern will cease to appear on the fabric at certain areas during each revolution, but by the proper selective control of plungers, the figures may be staggered or caused to appear in whatever manner the knitter desires. It is not considered necessary to go into the operation of the machine for producing other patterns since a great multitude of the same are possible and further examples would serve no purpose in this case.

It is further possible by the control of some plungers and not of others to form strips in the fabric showing one certain type of pattern work and adjacent thereto, other strips formed of an entirely different pattern, and thus to produce fabric which may have a center portion showing ornamentation of one kind and border portions plain or ornamented with an entirely different type of fancy work. Other possibilities are greater variation in the size of individual figures either in length or in width. By controlling plungers to inhibit the part of the pattern made at some only of the feeds, it is possible to make complete figures and then partial figures.

For purposes of illustration plungers, jacks, and jack cams have been shown which provide for corresponding needles knitting when selected, i. e., when plungers pushed in contact butts on the jacks, and either tucking or floating at other times. It is evident that the invention is applicable to the reverse condition, that is, where selected needles tuck or float, and it is intended that such a construction be covered in the claims of this case. The principles of the invention are also applicable to selective pattern work other than tucking and floating, e. g., such work as plating and floating, plating and reverse plating, and wrap striping. Such work as above outlined

is to be included in the term "ornamental stitches."

It is to be understood that the device herein described may work on jacks, needles, sinkers, pressers or any other knitting instrumentalities which enter into the production of ornamental fabric. It is quite clear that either sinkers or needles might be very effectively controlled for plating and reverse plating, and tuck and float work may be produced on spring needle machines, the pattern forming and pattern inhibiting means working upon pressers such as are commonly employed to press the beards of these spring needles.

The invention has been described with reference to a more or less specific form of the same and with a general description of the operation and different types of fabric that may be knitted, but these are to be taken as examples only and no limitations are intended to be imposed except those recited in the claims appended hereto.

I claim:

1. In a multi-feed knitting machine of the type described, the combination of knitting instrumentalities, one group of said knitting instrumentalities having removable butts thereon for purposes of selecting the same to control the forming of ornamental or patterned fabric, a plurality of selecting elements movable to and from a position wherein they will engage said removable butts, said plurality of selecting elements being divided into two groups, one group of said elements being manually controlled to form the basic design of the fabric and the other group of said elements having means associated therewith for moving them to and from butt engaging position, said means functioning with pattern controlling discs having removable butts thereon and a spindle for rotating said discs in timed relationship with the movements of said knitting machine whereby during certain revolutions of the machine some of said other group of elements will function to inhibit the production of said basic pattern.

2. In a multi-feed knitting machine the combination of a plurality of individual selector units spaced about the machine having pattern elements movable to and from active position and means associated with said support and elements for maintaining the elements in either position whereto they have been moved manually, other elements similar to those which are manually movable, a pair of spindles adjacent each said unit, levers on one spindle connected to said other elements and also functioning on pattern discs rotatable on the second spindle, a ratchet wheel on said second spindle and a pawl having means associated therewith for advancing said ratchet wheel during each revolution of the needle cylinder.

3. In a circular multi-feed knitting machine the combination of knitting instrumentalities, some of said instrumentalities being provided with removable butts for purposes of selection, a plurality of units spaced about said machine with superposed selecting elements individually arranged therein, said instrumentalities being relatively movable with respect to the selecting elements, the majority of the latter being individually and radially movable manually to and from butt engaging position and means functioning therewith to retain them in either of these positions, the remainder of said elements being under the control of selecting means which functions in timed relationship to the movements of said

knitting machine for the purpose of projecting these elements into butt engaging position to nullify the pattern being produced under the influence of the said majority of pattern elements.

5 4. In a circular multi-feed knitting machine, the combination of knitting instrumentalities, some of said knitting instrumentalities being provided with removable selecting butts for the knitting of patterned fabric, a plurality of individual selecting units spaced about the machine having supporting means, a series of plungers individually and radially movable to and from butt engaging position, means including a spring for maintaining some of said plungers in that position and for retaining said last mentioned plungers in an inactive position when moved thereto manually, others of said plungers being positively connected to pattern controlling means which functions in timed relationship to the movement of said knitting machine to nullify the knitting of patterned fabric.

5 5. In a circular multi-feed knitting machine a plurality of pattern elements including supports and a plurality of superposed selecting plungers movable to and from active position within said supports, one group of said plungers being manually movable to and from active position, means for maintaining the group of said plungers in active and inactive positions, said means including resilient means to maintain selected ones of the group of plungers in active position, other

plungers similar to those in the first group, a pair of spindles adjacent to the outer end of said plungers, levers individual to each of the second group of plungers, said levers rotating on one of the spindles and connected to the said other plungers at one end and having a toe thereon for engagement with pattern means rotatable on the second spindle, a ratchet wheel on said second spindle for rotating said pattern means, a pawl engageable with said ratchet wheel, a cam fixed to a rotating element of said machine and means for engagement with said cam and connected to said pawl for causing the same to advance the ratchet wheel and pattern means.

6. In a circular multi-feed knitting machine 15 the combination of a plurality of selector units, said units each having operatively associated therewith a plurality of pattern determining elements movable to and from an active position, said elements being divided into two groups, one group being manually and radially movable to and from an active position for selecting knitting instrumentalities to effect the knitting of a basic pattern, the other group of said elements being movable by pattern means movable in timed relation to the movement of knitting instrumentalities within said knitting machine, for controlling this other group of elements to nullify the pattern tending to be produced under the influence of said manually controlled pattern elements. 30

ROBERT H. LAWSON.
